United States Patent Office.

EDWIN MAY, OF INDIANAPOLIS, INDIANA.

Letters Patent No. 88,972, dated April 13, 1869.

IMPROVEMENT IN SHEET-METAL-LATH MACHINE.

The Schedule referred to in these Letters Patent and making part of the same.

To all whom it may concern:

Be it known that I, EDWIN MAY, of Indianapolis, in the county of Marion, and State of Indiana, have invented a new and useful Machine for Forming Sheet-Metal Laths for fire-proofing buildings; and I do hereby declare that the following is a full, clear, and exact description thereof, that will enable skilled artisans to make and use the same, reference being had to the accompanying drawing, and to the letters of reference marked thereon, making part of this specification.

This invention relates to device for forming sheet-metal laths to be used in rendering buildings fire-proof, having for its object to simplify and lessen the cost of their manufacture, to the end that their application may be rendered more practicable, and hence become more general; and

It consists in the employment of a fixed jaw and a movable jaw hinged thereto, and having projections and recesses, arranged in such relation to each other, as, when closed upon them, to give strips of sheet-metal the desired form; and

It further consists in the arrangement and mode of operation of a device connected with the forming-device, by which metal furring-studs, when desired, may be expeditiously and conveniently attached to the laths simultaneously with giving them the required form.

Figure 1 is a side elevation of the machine.

Figure 2 is an end view of the same, closed.

Figure 3 is an end view of the same, open.

Figure 4 is a top view of the same, open.

Figure 5 is a rear view of the machine.

Figure 6 is an end view of several laths, as formed by the machine, attached, both with and without the furring-studs, to the under side of floor joists.

Figure 7 represents end, section, and side views of the furring-studs.

Similar letters of reference indicate corresponding parts in the several figures.

The machine is composed of the fixed jaw A and the movable hinged jaw B, furnished with the moulding projections C C and recesses D D, as shown in figs. 2 and 3, which mould the sheet-metal into the desired form for the lath.

The movable jaw B is hinged at E, in the manner shown, so that the projection and recess of this jaw will separate from the projection and recess of the fixed jaw, as shown in fig. 3.

When it is designed to use furring-studs, as shown in fig. 6, for holding the laths off the joists and wall-studding, it becomes desirable to attach them to the laths in the proper places, with the least practicable expenditure of time and labor.

This I accomplish by providing recesses at the required distances apart, as shown at F, fig. 4, and indicated by dotted lines in figs. 1, 2, 3, and 5, to receive the furring-studs, and opposite these, in the movable jaw, arranging a triangular pointed punch, G, which may be operated by a lever, H, or other convenient means, with which to pierce the lath and turn the burr into the small hole in the end of the stud, where it is clinched by driving the punch still further into the stud.

In order to feed the furring-studs into the recesses F, it is designed to place them in an inclined groove in the upper edge of jaw A, as indicated by the dotted lines in figs. 1, 2, 4, and 5, down which they will roll, by their own gravity, into the recess opposite the punch.

The fixed jaw A is also furnished with adjustable stops J, upon which the lower edge of the sheet-metal strips, of which the laths are formed, rests, and is held in place until clamped by the jaws.

As soon as the jaws are brought together to form the lath, the punch G is driven through it, and, being triangular pointed, cuts three burrs that are turned into the small hole in the end of the stud, which, by forcing the punch still further, clinches the burrs inside of the stud, thus securing it to the laths in a manner sufficient to retain it through the vicissitudes of handling and nailing them to the joists or studding, thus making the application of these metallic furring-studs comparatively inexpensive, so far as relates to the time and labor required to attach them.

It will be understood, of course, that the moulding-jaws A B are to be made of such length as to form the laths of any desired length, and that the recesses for the studs and the punches for attaching them to the laths will be spaced the proper distance for the joists or studding.

It will be seen from fig. 6, that the laths are formed so that, when nailed to the joists or studs, the side of the lath next to them forms a continuous surface of sheet-metal that serves both to keep the mortar from going through, and, when used for the ceilings, as a floor, upon which to lay mortar on the upper side between the joists, and that the outer or under surface is such as to hold a sufficient quantity of mortar to form a substantial key to hold the plaster.

The peculiar form required for sheet-metal laths to subserve these purposes, renders them difficult and expensive to manufacture, and, hence, the utility of a machine so constructed and operating to give them the required form in a simple manner, and with such rapidity as to make them as cheap as practicable.

Having thus fully described my invention,

What I claim as new, and desire to secure by Letters Patent, is—

1. The jaws A B, furnished with the moulding projections and recesses C D, for giving the laths, substantially, the form shown, and arranged to operate substantially as herein set forth.

2. In combination with the jaws furnished with the moulding projections and recesses C D, the piercing and setting punch G, for attaching the furring-studs to the laths, substantially as set forth.

3. The combination of the punch G with the recess F, arranged to operate in the manner substantially as set forth.

EDWIN MAY.
